UNITED STATES PATENT OFFICE

WILLIAM G. EHRHART, OF CHICAGO, ILLINOIS

DESIGN FOR A POOL TABLE

Application filed May 1, 1931. Serial No. 39,673. Term of patent 7 years.

To all whom it may concern:

Be it known that I, WILLIAM G. EHRHART, a citizen of the United States, residing at Chicago, in the county of Cook, and State of Illinois, have invented a new, original, and ornamental Design for a Pool Table, of which the following is a specification, reference being had to the accompanying drawing, forming part thereof.

The figure is a perspective view of a pool table showing my new design.

I claim:

The ornamental design for a pool table, as shown.

WILLIAM G. EHRHART.
